[57] CLAIM

The ornamental design for a necklace pendant circlet, substantially as shown and described.

DESCRIPTION

FIG. 1 is a front elevational view of a necklace pendant circlet showing my new design;

FIG. 2 is a right edge elevational view thereof;

FIG. 3 is a rear elevational view thereof;

FIG. 4 is a top plan thereof;

FIG. 5 is a bottom plan thereof;

FIG. 6 is a top perspective view thereof;

FIG. 7 is a front elevational view of a necklace pendant circlet showing a second embodiment of my new design;

FIG. 8 is a right edge elevational view of FIG. 7;

FIG. 9 is a rear elevational view of FIG. 7;

FIG. 10 is a top plan view of FIG. 7;

FIG. 11 is a bottom plan view of FIG. 7;

FIG. 12 is a top perspective view of FIG. 7;

FIG. 13 is a front elevational view of a necklace pendant circlet showing a third embodiment of my new design;

FIG. 14 is a right edge elevational view of FIG. 13;

FIG. 15 is a rear elevational view of FIG. 13;

FIG. 16 is a top plan view of FIG. 13;

FIG. 17 is a bottom plan view of FIG. 13;

FIG. 18 is a top perspective view of FIG. 13;

FIG. 19 is a front elevational view of a necklace pendant circlet showing a fourth embodiment of my new design;

FIG. 20 is a right edge elevational view of FIG. 19;

FIG. 21 is a rear elevational view of FIG. 19;

FIG. 22 is a top plan view of FIG. 19;

FIG. 23 is a bottom plan view of FIG. 19;

FIG. 24 is a top perspective view of FIG. 19;
